UNITED STATES PATENT OFFICE.

ROBERT J. ZORGE, OF CHICAGO, ILLINOIS, ASSIGNOR TO ZORGE SAFETY RAILWAY EQUIPMENT COMPANY, OF CHICAGO, ILLINOIS, A CORPORATION OF ILLINOIS.

ALARM-SIGNAL.

No. 845,991.

Specification of Letters Patent.

Patented March 5, 1907.

Application filed February 28, 1906. Serial No. 303,487.

To all whom it may concern:

Be it known that I, ROBERT J. ZORGE, a citizen of the United States, residing at Chicago, in the county of Cook and State of Illinois, have invented a new and useful Improvement in Alarm-Signals, of which the following is a specification.

My invention relates particularly to means for giving warning to an engineer or motor-man approaching an open switch or an open draw with his train or car; and my primary object is to provide improved apparatus involving the use of a device which will be preparatorily set when the switch is thrown open and which will operate to detonate a torpedo or explosive body when a train passes over in approaching the switch.

The invention is illustrated in the accompanying drawings, in which—

Figure 1 represents, diagrammatically, a portion of a railway-track equipped with my improved alarm device; Fig. 2, an enlarged view showing a fragment of a rail, the mechanism of my apparatus applied thereto, and the relation of a car or engine-wheel to the mechanism, the front plates of the casing being broken away and a portion of the casing shown in section; Fig. 3, a section taken as indicated at line 3 of Fig. 2; Fig. 4, a broken view illustrating a different position of the parts shown in Fig. 2; and Fig. 5, a broken view of a sound-conducting pipe which leads from the casing of the mechanism and rises to a point above and at one side of the track.

In the construction illustrated, A represents the main line of a track; B, a side track; C, a switch-point operated by any convenient means, (not shown,) and D, my improved device electrically connected with the track and the switch-point thereof and operating to cause a series of explosions in the event that a train passes over while the switch is open.

The device D preferably comprises a casing d, arranged adjacent to the inner side of one of the rails a of the track at a distance (one mile, more or less,) from the switch-point, said casing being equipped on the side away from the rail with removable plates d' d'' d'', a rotary torpedo-carrier d⁴, fixed to a shaft d⁵, extending transversely of and journaled in the casing, a ratchet-wheel d⁶, fixed on said shaft, serving as a means for rotating the

torpedo-carrier, a plunger or striker d⁷, 55 mounted in the upper portion of the casing and having a tread portion d⁸ located adjacent to the upper flange of the rail in position to be engaged by the flange of a wheel d⁹, a pawl d¹⁰, carried by the plunger d⁷ and adapted to actuate the torpedo-carrier through the medium of the ratchet-wheel d⁶, a spring d¹¹, tending to hold the pawl in engagement with the ratchet-wheel, an electromagnet d¹², having a plunger d¹³ connected with the pawl d¹⁰, a pawl-retracting lever d¹⁴, supported on a pivot d¹⁵, carried by a standard d¹⁶, said lever forming the armature of an electromagnet d¹⁷, a spring d¹⁸, tending to hold the armature d¹⁴ away from its magnet, a yielding contact member d¹⁹, carried by a standard d²⁰, a pipe d²¹, communicating with an opening d²² in the casing-plate d³, said pipe having a horizontal portion d²³, extending through the road-bed and beneath the rail a' at the other side and having a standing portion d²⁴ with an inturned bell-shaped end d²⁵, which in practice is located at a point adapted to convey sound as near as possible to the cab of an engine passing over the track, a main electric circuit d²⁶, including as a part thereof the solenoid of the magnet d¹² and having a battery d²⁷, one terminal of the circuit being connected with the switch-point C and the other with the rail a, and an auxiliary electric circuit d²⁸, equipped with a generator d²⁹, said circuit having one of its conductors d³⁰ divided into branches d³¹ d³², one of which is in electrical connection with the rotary torpedo-carrier d⁴ and the other with the armature-lever d¹⁴.

The wheel or carrier d⁴ is equipped on one side with a ring d³³, of insulating material, through which project studs d³⁴, of conducting material, carried by the wheel, said studs being adapted to complete the circuit d²⁸ through a yielding contact member d³⁵, carried by a standard d³⁶, mounted on a block of insulating material d³⁷, the standard d³⁶ being joined by a conductor d³⁸ to the circuit d²⁸. The circuit d²⁸ includes two contact-points d³⁹, mounted upon an insulating-strip d⁴⁰, with which the magnet d¹² is equipped at one end, and a movable contact member d⁴¹, carried by the free end of the plunger d¹³. The function of the magnet d¹⁷, which is included in the electric circuit d²⁸, is to retract the

pawl d^{10} after the carrier has been actuated a predetermined number of times during the passing of a train, thereby to prevent waste of torpedoes.

- 5 I have shown the casing d equipped at one side of its upper portion with an enlargement d^{12} , which bears upon the web of the rail and fits snugly between the top flange and bottom flange of the rail, the bottom flange of the rail being recessed to receive the wall d^{43} of the casing. The casing is secured to the rail by bolts d^{44} and may, if desired, be secured to the ties (not shown) which support the rails. The casing is preferably divided 15 into two chambers d^{45} d^{46} by a transverse vertical wall d^{47} , the plunger d^{13} of the magnet d^{12} extending through a perforation d^{48} in said wall. The plate d' covers the chamber d^{46} , and the plates d^2 d^3 cover the chamber d^{45} . 20 In the present construction I have shown the wheel d^4 flattened peripherally at ten equidistant points d^{49} , affording sockets thereat for torpedoes d^{50} . These sockets are shown equipped at one side with flanges d^{51} 25 and at the other side with springs or yielding flanges d^{52} , providing for the ready insertion of the torpedoes, the torpedoes themselves being provided with flanges adapted to slide beneath the flanges d^{51} d^{52} . The ratchet-wheel d^6 is correspondingly equipped with ten teeth, the teeth being so arranged that when the pawl d^{10} is at the upper end of its stroke a torpedo will be presented beneath the plunger or striker d^7 . The torpedo-carrier 30 may be charged by removing the plate d^2 of the casing, or any other suitable provision for charging the carrier may be made. Ordinarily in charging the carrier one socket is left uncharged, so that no explosion will occur in the normal working of the device unless the switch-point be open.

The plunger or striker d^7 is provided within the casing with a flange d^{53} , supported on a spring d^{54} , carried by a bracket d^{55} , located in 45 the upper portion of the casing. In the lower portion of the member d^7 is formed a chamber d^{56} , in which works a yielding striking member d^{57} , between whose flanged head and the upper end of the chamber d^{56} is confined a spring d^{58} . The normal movement of the member d^7 is sufficient to cause the member d^{57} to strike the presented torpedo and cause an explosion. By providing a yielding striking member a variable movement of 50 the member d^7 is allowed for, such provision being desirable on account of the variation in the flanges of the car-wheels.

The lower end of the member d^7 is shown equipped with a projecting arm d^{59} , upon 60 which is mounted an arm d^{60} , having a slot d^{61} in its end, in which the upper end of the pawl d^{10} is carried by a pivot d^{62} . When the pawl is held in the position shown in Fig. 2, its movement toward the ratchet-wheel is 65 limited by a shoulder d^{63} . The slot is cut

deeper at its upper portion to permit the pawl d^{10} to swing to the position shown in Fig. 4 when the circuit d^{28} is closed to throw the pawl out of working engagement with its ratchet-wheel. 70

The operation may be explained briefly. When the switch-point C is closed, the circuit d^{26} normally energizes the magnet d^{12} and withdraws the pawl d^{10} from working engagement with the ratchet-wheel. The 75 spring d^{11} , however, tends normally to hold the pawl in working engagement with the ratchet-wheel, so that in the event of the breaking of the circuit d^{26} , either through the opening of the switch or through injury to 80 the circuit, the device will operate when a train passes over to give an alarm-signal. Assuming the torpedo-carrier to be preparatorily charged with torpedoes, except at the uppermost point, and assuming the device to 85 be in its normal working condition, a train will pass over the device without receiving an alarm, provided the switch-point is closed. If the switch-point is open, however, the magnet d^{12} will be deenergized, allowing the spring 90 d^{11} to bring the pawl d^{10} into working engagement with the ratchet-wheel d^6 . When the first wheel of the train passes over the striker d^7 , it depresses the striker, causing the pawl to engage a fresh tooth of the ratchet-wheel. 95 Upon the return movement of the striker under the action of its spring the pawl d^{10} is elevated, thereby moving the torpedo-carrier one space and bringing a torpedo beneath the striker. When the next wheel passes over 100 the striker, the striker operates to explode a torpedo. As the wheels pass in succession over the striker the torpedo-carrier will be intermittently rotated and explosions will occur until a stud d^{34} encounters the contact 105 member d^{35} , when the circuit d^{28} will be closed, thereby energizing the magnet d^{17} and causing the armature-lever d^{14} to throw the pawl d^{10} out of operative engagement with the ratchet-wheel, whereupon the remainder 110 of the train will pass over the device without causing further explosions. It should be stated, however, that the force of the spring d^{18} and the strength of the magnet d^{17} bear such relation to each other that the pawl d^{10} 115 will not be thrown out of engagement with the ratchet-wheel until it completes its upward movement, thereby causing the stud d^{34} , which served to complete the circuit d^{28} , to move out of engagement with the contact 120 member d^{35} , it being observed, however, that before this occurs the lever d^{14} contacts with the yielding contact member d^{19} , included in the circuit d^{28} , so that the circuit is maintained. Said circuit is maintained until the 125 switch-point is closed, thereby energizing the magnet d^{12} again and moving the contact member d^{11} away from the points d^{39} , thereby breaking the circuit d^{28} and deenergizing the magnet d^{17} . This frees the pawl d^{10} from 130

the restraining action of the armature-lever d^{14} , so that the pawl is free to return to working engagement with the ratchet-wheel when the circuit of the magnet d^{12} is broken again, 5 as by the opening of the switch-point.

It is expected that train crews will ordinarily be instructed to attend to the recharging of the detonating device whenever an alarm is given. However, in the construction 10 shown provision is made for the continued operation of the device until three trains have passed thereover, even though one or more of the train crews should neglect the duty imposed by the instructions. This 15 is an additional feature of safety, and it is obvious any number of operations of the device within reasonable limits may be provided for.

It is deemed a feature of great importance 20 in the electrically-controlled detonating device described that the device will operate even in the event of the failure of the controlling-circuit.

The spacing of the studs d^{34} is such that 25 the circuit d^{28} will be completed after each third actuation of the torpedo-carrier. The position shown in Fig. 2 is that which the device occupies after the carrier has been moved to withdraw its uncharged chamber 30 from beneath the striker d^7 and bring a charged chamber beneath the plunger. It will be obvious, therefore, that during the second movement of the carrier from the position shown in Fig. 2 the stud d^{34} above the 35 contact member d^{35} will complete the circuit d^{28} through said contact member and then break said circuit at the contact member after contact has been established at the contact member d^{19} .

40 I have provided an auxiliary safety feature intended to guard a train moving in the direction of the arrow shown in Fig. 1 in the event that a train leaving the side track B and passing in the direction opposite the 45 direction indicated by the arrow fails to stop and reset the detonating device. This comprises a circuit F, connected with the circuit d^{28} on opposite sides of the magnet d^{17} and connected with the track A at a point farther 50 removed from the switch than is the detonating device. This circuit includes a contact-point f and a normally vertical spring-held switch f' , adapted to be actuated by a wheel of a car to close the circuit when the train

55 moves in the direction indicated by the arrow. Assuming, then, that the switch-point has been left in an open position after the magnet d^{17} has operated to retract and maintain in a retracted position the pawl d^{10} of the 60 ratchet mechanism, a train moving in the direction indicated by the arrow will close the branch auxiliary circuit F, thereby short-circuiting the battery d^{29} and deenergizing the magnet d^{17} , thus permitting the pawl d^{10} to return to its operative position in engagement 65

with the ratchet-wheel. When the train, therefore, continuing its movement, passes over the detonating device, the latter will operate to give warning of the open switch. I have also shown the detonating mechanism 70 equipped with an auxiliary circuit G, provided with a bell g and a battery g' , the bell being understood to be located in a station for the purpose of giving warning when the torpedoes in the detonating device have become exhausted. This is accomplished by providing the rotary torpedo-carrier with a contact-point g^2 , which makes contact with a member g^3 , the carrier being electrically connected with one conductor of the circuit G 75 through the casing d , and the member g^3 being electrically connected with the other conductor of the circuit G. The arrangement is such that after the torpedo-carrier has moved through nine spaces the circuit G 80 has been completed, causing the bell to ring. It is expected that when the torpedo-carrier is charged it will always be set at a given position, and indicating means may be provided, showing what the position should be. 85

In Fig. 3 I have shown the casing equipped with a spring-pressed catch H, serving to engage suitably-spaced perforations h , with which the rotary carrier is equipped, thereby to lock the wheel yieldingly at its points of retardation to prevent movement of a wheel under its own inertia. 90

It is essential to the successful operation of the device that it have an electrically-controlled movable member, and the electrically-controlled movable member is preferably a torpedo-carrier. A feature of considerable importance also is that of a striker actuated by a wheel or other member of the moving train, although it would be within the scope 100 of my invention to adapt the carrier to move the torpedo directly over a rail, so that it would be crushed between the rail and a wheel passing over it. 105

It is obvious that many changes in details 110 of construction within the spirit of my invention may be made, so that the foregoing detailed description should be understood as having been given for clearness of understanding only. 115

The improved device may be usefully employed in connection with switches, drawbridges, visual signals, crossings, and in various other situations.

What I regard as new, and desire to secure 120 by Letters Patent, is—

1. The combination of a torpedo-carrier, a spring-held striker adapted to be struck by a train, means connected with said striker for actuating said carrier, an electromagnet controlling said means, and an electric circuit controlling said magnet. 125

2. The combination of a rotary torpedo-carrier equipped with a ratchet-wheel, a striker equipped with a pawl, a magnet con- 130

- trolling said pawl, a main circuit controlling said magnet, an auxiliary magnet controlling said pawl, and an auxiliary circuit controlled by said first-named magnet.
- 5 3. The combination of a rotary torpedo-carrier equipped with a plurality of contact members, a ratchet-wheel, a striker, equipped with a pawl, an electromagnet controlling said pawl, a main electric circuit controlling said magnet, an auxiliary electromagnet controlling said pawl, an auxiliary electric circuit controlling said auxiliary magnet and controlled by said first-named magnet, and a contact member connected with said auxiliary circuit and coacting with the contact members of said rotary carrier,
- 10 4. The combination of a rotary torpedo-carrier equipped with a plurality of contact members, a stationary contact member coacting therewith, a pawl serving to actuate said rotary carrier, a main electromagnet controlling said pawl, a main electric circuit controlling said magnet, and an auxiliary magnet controlling said pawl and having a controlling- 40
- 15 circuit controlled by said first-named magnet, said auxiliary circuit being closed by the movement of the rotary carrier and having means for maintaining a closed circuit after the contact with the carrier has been broken.
- 20 5. The combination with a railway-track, of means of the character set forth, comprising a torpedo-carrier, a main electric circuit controlling said carrier, a switch-point controlling said circuit, an auxiliary circuit controlled by said carrier and by the main cir- 45
- cuit, and train-controlled means controlling said auxiliary circuit.
6. The combination with a railway-track having a movable switch-point, of a device for the purpose set forth, comprising a torpedo-carrier, a striker, actuating means moving with the striker, a main electric circuit controlled from the switch-point and having a magnet controlling said actuating means, an auxiliary electric circuit controlled by said magnet and by said carrier, said auxiliary circuit having a magnet controlling said actuating means, and a branch auxiliary circuit equipped with means whereby it may be closed by a train to short-circuit the auxiliary 50 magnet, for the purpose set forth.
7. The combination with a railway-track having a movable switch-point, of a device for the purpose set forth, comprising a movable torpedo-carrier, train-actuated means 55 for actuating the torpedo-carrier, and an electric circuit controlled by the switch-point and controlling the actuating means of the torpedo-carrier.
8. In a device for the purpose set forth, the combination of a rotary carrier equipped with means for holding a plurality of torpedoes, an electric circuit controlling said carrier, and an electric circuit provided with means for giving notice when the carrier requires recharg- 60
- 65 ing.
